N. J., a corporation of Delaware

Application July 27, 1944, Serial No. 546,764

19 Claims. (Cl. 103—182)

The present invention relates to pumps and more particularly to a novel structure for radial piston pump of the high pressure type.

In the use of the term high pressure is meant pressures in excess of 3000 lbs. Heretofore, it has been difficult to provide a pump for operation at such high pressures due to the inertia of the moving parts and the attendant peripheral velocities of the bearing surfaces.

In order to overcome the foregoing difficulties, an object of the invention is to provide a crank shaft of relative small diameter for operating a plurality of shoes which have for their bearing surface a recess filled with hydraulic fluid. The fluid serves as a hydraulic bearing between the shoes and an eccentric or abaxial actuating member, while the shoes serve as seals for the bearing fluid and as supports for radially extending pump pistons.

Another object of the invention is to provide a novel radial piston pump which will supply hydraulic fluid at high pressures for use in hydraulic systems particularly in aircraft.

Another object of the invention is to provide a compact pump of great efficiency in comparison to its size and of such simplicity in construction as to adapt it for convenient and rapid manufacture and assembly at low cost.

Another object of the invention is to so arrange the oil bearing in relation to the pump piston that neither floating of the shoes, nor seizure between the shoes and crank shaft will result at the high speeds and pressures to which the pump pistons are subjected.

Another object of the invention is to provide a novel fitting for the shoe and piston, whereby the shoe and piston may readily wear to a superior fit and seal with continued operation.

Another object of the invention is to provide a hollow piston sleeve having a wall of such material and thickness as to be readily adapted to effect a limited expansion with high pressures for reducing the clearance between the piston and cylinder wall in order to maintain between the piston and cylinder wall a substantially negligible leakage upon pressure increase.

Another object of the invention is to provide novel means for connecting a plurality of pump pistons in driving relation along the periphery of an eccentric driving member.

Another object of the invention is to provide a novel ring means for securing the pump pistons in driving relation along the periphery of an eccentric driving member so as to transmit movement from the eccentric to the pistons.

The above and further objects and novel features of the invention will more fully appear from the following detailed description and the accompanying drawings wherein one embodiment 10 of the invention is illustrated. It is to be expressly understood, however, that the drawings are for the purpose of illustration only and are not designed as a definition of the limits of the invention, reference being had for this purpose 15 to the appended claims.

In the drawings, wherein like reference characters refer to like parts in the several views,

Figure 1 is a perspective view of a pump embodying my invention with a portion thereof 20 broken away so as to better illustrate the inner arrangement of the same;

Figure 2 is a longitudinal sectional view of a preferred form of pump embodying my invention;

Figure 3 is a view of one end of the pump 25 shown in Figure 2;

Figure 4 is a view of the opposite end of the pump from that shown in Figure 3;

Figure 5 is a somewhat diagrammatic cross-sectional view illustrating the arrangement of the 30 pump pistons about the eccentric operating member;

Figure 6 is a fragmentary view of the fastening clip for the novel piston connecting ring;

Figure 7 is an enlarged fragmentary sectional 35 view illustrating the relationship between the piston and shoe; and

Figure 8 is a fragmentary sectional view of Figure 7.

Referring now to the drawings, the invention 40 will be described as applied to the pump shown in Figure 2, like numerals, however, indicating like parts in the form shown in Figure 1.

As shown, there is provided a housing, casing or casting 1 having formed therein a pump chamber 2. End plates 3 and 4 are mounted at opposite ends of the casting 1 by suitable bolts 5 and 6 respectively.

The end plate 3 has rotatably mounted therein a shaft 7 on which are mounted eccentric or abaxial actuating members indicated by the nu- 50

meral 8 and positioned in the chamber 2. A flexible coupling member 9 is suitably connected at the outer end of the shaft 7 and arranged to connect the shaft 7 to a suitable driving motor not shown. The shaft 7 is mounted at the opposite ends in suitable anti-friction bearings 10 and 11 carried by the end plates 3 and 4, respectively.

The end plate 4 has provided thereon inlet and outlet connectors 12 and 13, respectively. The inlet connector 12 is arranged to be connected to a suitable source of fluid medium such as oil and leads through a passageway 14 formed in the end plate 4 into a passageway 15 extending longitudinally in the shaft 7.

The inlet passageway 15 is formed concentric with the axis of rotation of the shaft 7. Arcuate slots 16 lead radially from the passageway 15 and open at the peripheral edge of the respective eccentric members 8. Slidably mounted along the peripheral edge of each of the eccentric members 8 are a plurality of shoes each indicated generally by the numeral 17. Each of the shoes 17 is curved at the inner surface so as to slide along the periphery of the cooperating eccentric member 8 and has provided a recess 18 formed in the inner surface surrounded by an outer edge 19B, as best shown in Figures 7 and 8. A passage 20 extends through the shoe 17 from the recess 18 and is arranged to cooperate with the passage 16, upon the eccentric member 8 being turned so as to position the opening 16 opposite the opening 18.

Further formed in the shoe 17 at the outer side thereof is a recess or seat 21 having a spherical radius. Riding within the recess 21 is a semi-spherical end 22 of a piston sleeve member 23. The piston sleeve 23 is open at the opposite ends thereof, and is arranged to slidably move within a cylindrical chamber 24.

Two sets of cylindrical chambers 24 are drilled in the casting 1 and radiate from the chamber 2 from points opposite the respective eccentric members 8, as possibly best shown in Figures 1, 2, and 5. Reciprocably mounted in the cylindrical chambers 24 are the piston sleeves 23. The outer ends of the cylindrical chambers 24 are closed by plugs 25 which are positioned on resilient seat member 26. The plugs 25 have projecting inwardly therefrom stems 27. The stems 27 cooperate with corresponding piston sleeves 23 so that upon outward reciprocal movement of the piston sleeve 23 the stem projects into the open end of the sleeve 23 forcing the hydraulic fluid therefrom, as will be explained. An outer casing or shell 28 fits tightly about the outer surface of the casting 1, securing the plugs 25 in position in the cylinders 24.

Provided within the sleeve 23 is a shoulder 29 on which rests a pin 30, pivotally connecting to the sleeve 23 on one end of a rod 31. The rod 31 has the opposite end thereof pivotally connected to its corresponding shoe 17 by a pin 32 inserted in a hole 33 which opens at opposite sides of the shoe 17 into arcuate slots 34 formed therein.

Due to the novel semi-spherical shape of the end 22 of the piston sleeve 23 and the recess 21 in which the end 22 is seated, the piston sleeve 23 and shoe 17 are self-aligning at all times so that the connecting rod 31 for the piston 23 does not carry any appreciable load during the compression stroke of the piston sleeve 23. Therefore, the connecting rod 31 need only be provided of a size and strength ample to carry the relative light load of returning the piston sleeve 23 on the suction stroke.

As shown in Figure 8, the pins 32 are locked in position in the shoes 17 by bands or rings 35, which are positioned in the arcuate slots 34 at opposite sides of the shoes 17, so as to hold the shoes in engaging relation along the periphery of its corresponding eccentric member 8. Three flexible clips 36, as shown in Figures 5 and 6, are provided for fastening the rings in position. Each clip 36 has a projecting clip part 37, which is first positioned under the lower edge of one ring 35 and the other end then snapped over the other ring 35, as shown in Figure 6, so as to fasten the rings 35 in position and the shoes 17 in contacting relation along the surface of the eccentric member 8.

It will be seen that surrounding the recess 18 formed in the inner surface of the shoe 17 is the edge 19B adapted to engage the surface of the eccentric member 8 and seal within the recess 18 the aforementioned hydraulic fluid.

The hydraulic fluid carried within the recess 18, thus serves as a bearing, and the shoe 17 through the edge 19B serves as a seal for such bearing fluid. It will be seen, however, that under pressure the hydraulic fluid will tend to spread under the edge 19B lubricating the surface between the edge 19B and the surface of the eccentric 8. However, in order to prevent the shoe 17 from tending to "float" under the extreme hydraulic pressures and speeds to which the pump is subjected, the surface area of the shoe 17 subject to such floating pressure is matched against the total surface area of the piston 23 exposed to a counteracting fluid pressure so that the total area of the shoe 17 under a fluid pressure tending to float the shoe 17, will be less than the total surface area tending to hold the shoe in contacting relation with the eccentric member 8. Thus the fluid pressure applied through the piston 23 will exert a counteracting force tending to force the shoe 17 toward the eccentric member 8. However, the difference between such counteracting pressure areas is sufficiently small and the bearing area between the edge 19B and eccentric member 8 sufficiently great, that seizure will not result at the high velocity and pressures at which the pump is operated. The structure of the shoe 17, illustrating my novel fluid bearing arrangement in relation to the piston 23, is probably best shown in Figures 7 and 8, wherein the comparative area of the shoe 17 under fluid pressure tending to float the same is indicated by the line X-X, while the comparative surface area of the piston 23 subject to fluid pressure tending to counteract the latter force is indicated by the line Y-Y.

In the event the hydraulic fluid to be used is water, the shoe 17 may be formed of any suitable material lubricated by water such as Bakelite. Where oil is used, the shoe 17 may be formed of leaded phospho-bronze or any other suitable material lubricated by oil.

I have further provided an additional novel feature in my invention in that the piston sleeve 23 is formed of a suitable expansible material, such as steel. The wall of the piston sleeve 23 is further formed sufficiently thin between the shoulder 29 and end 23A, that a minute limited expansion of the latter portion of the wall of the piston sleeve 23 will result at the high pressures and thereby reduce the clearance between the piston sleeve 23 and the cylinder wall 24 when subjected to such high pressures. The latter expansion is sufficiently limited, however, as not to effect seizure between the piston sleeve and cyl-

inder wall. Thus there is maintained a substantially negligible leakage between the piston sleeve 23 and the cylinder wall 24 as the fluid pressure within the cylinder increases.

As shown in Figures 1 and 2, an outlet passage 38 formed in the casting 1 leads from the cylindrical chambers 24, into a second passage 39 formed in the end plate 4, which passage 39 in turn opens into a main collecting passage 40 formed in the end plate 4. The main collecting passage 40 leads through a passage 41 into the outlet connector 13, which is arranged for connection to a suitable outlet conduit not shown.

A check valve 42 is positioned between each of the passages 38 and 39 and is biased to a closed position by a spring 43 which is counteracted by outlet pressure from its corresponding cylindrical chamber 24. The check valve 42 is biased to a closed position upon suction pressure being exerted in the corresponding cylindrical chamber 24.

The aforesaid pump mechanism provides novel means for facilitating the convenient and rapid assembly of the mechanism. Thus in assembly, the pin 30 is first inserted together with the rod 31 into the outer end of the piston 23 so that the pin 30 rests on the shoulder 29 and the rod 31 extends through the opposite end of the sleeve 23. The ends 22 of the pistons 23 are then seated in the respective recessed portions 21 of the shoes 17 and the pin 27 inserted in the holes 33 in the shoe 17 so as to engage in the rod 31. The two sets of shoes 17 and pistons 23 may then be assembled in position by a ring 35, which is placed in each case at the opposite side from that of the open ends of the casting 1. The eccentric members 8 may then be inserted into chamber 2 in operative relation to the shoes 17, whereupon the companion rings 30 may then be placed in the groove 29 of the shoes 17 adjacent the opposite ends of the shaft 7. The two rings 35 may then be fastened in position by means of the snap clip 36, as explained, whereupon the pistons 22 are then assembled for operation upon the fastening of the end plates 3 and 4 in position at the opposite ends of the casting 1, as shown in Figures 1 and 2.

In operation it will be seen that upon rotation of the shaft 7 oil or other suitable hydraulic fluid medium will be drawn into the passageway 15 through the connector 12, flooding the interior of the chamber 2 through the passageways 16 opening into the chamber 2.

Due to the nature of the eccentric members 8 and the corresponding slots 16, it will be seen that the same when rotated will constitute a centrifugal pump having a supercharging effect, whereby there is provided a charging head which is greater than the pressure at the inlet 12.

Moreover, upon rotation of the eccentric members 8 by the driving shaft 7 the shoes 17 following the periphery of the eccentric members 8, due to the action of the rings 35, will cause the corresponding pistons or sleeves 23 connected to the shoes 17 by the rods 31 to reciprocate in their respective cylindrical chambers 24. Movement of the sleeves 23 inwardly toward the shaft 7 will cause a partial vacuum to be set up within the cylindrical chamber 24. Thus upon the arcuate slot 16 coinciding with the opening 19 of the shoe 17, as shown in the Figure 5, the fluid medium supplied through the passage 15 will be drawn by suction and under pressure of the charging head aforesaid, into the cylindrical chamber 24.

Upon further rotation of the eccentric members 8 causing an opposite reciprocating move-

ment of the piston 23 in the cylinder 24, the stem 27 will project into the sleeve 23 displacing the fluid medium within the piston sleeve 23 and cylindrical chamber 24 so as to force the fluid medium into the passage 38. The check valve 42 under force of the fluid medium will then be biased to an open position, whereupon the fluid medium will pass under pressure of the pistons 23 through the passages 38 and 39 and 40 and out the outlet 13.

Although only two embodiments of the invention have been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

20. 1. A pump comprising a casing, a main chamber provided therein, an eccentric member rotatably mounted in said chamber, a radially directed secondary chamber provided in said casing, a radially directed piston sleeve reciprocably mounted in said secondary chamber, co-operating fluid inlet port means provided in the eccentric member and periodically opening into said piston sleeve for supplying under centrifugal force a fluid medium through said sleeve to said secondary chamber, fluid outlet means from said secondary chamber, and means operably connecting said piston sleeve to said eccentric member for imparting a reciprocating movement thereto.
25. 2. A pump comprising a casing, a main chamber provided therein, an eccentric member rotatably mounted in said chamber, a set of radially directed secondary chambers provided in said casing, a set of radially directed piston sleeves reciprocably mounted in said secondary chambers, a set of shoes slidably positioned on said eccentric members each of said pistons having an end operably connected to one of said shoes, means operably connecting said shoes to said eccentric member whereby upon rotation of said eccentric member reciprocable movement may be imparted to said pistons, fluid conduit means provided in said shoes and eccentric member for conducting a fluid medium into said sleeves and thereby into said secondary chambers, and fluid outlet means for said secondary chambers.
30. 3. A pump comprising a casing, a main chamber provided therein, an actuating member rotatably mounted in said chamber, a set of radially directed secondary chambers provided in said casing, a set of radially directed pistons reciprocably mounted in said secondary chambers, fluid inlet and outlet means for said secondary chambers, a set of shoes slidably positioned on said actuating member, each of said shoes having a recess formed in the outer surface thereof and said recess having a spherical radius, each of said pistons having a semi-spherical end positioned in one of said recesses, coupling means for pivotally connecting said pistons to said shoes, and means operably connecting said shoes to said actuating member, whereby upon rotation of said member reciprocable movement may be imparted to said pistons.
35. 4. A pump comprising a casing, a main chamber provided therein, an eccentric member rotatably mounted in said main chamber, a radially directed secondary chamber provided in said casing, a piston sleeve reciprocably mounted in said secondary chamber, a shoe slidably positioned on

said eccentric member, said piston sleeve having an end operably connected to said shoe, means operably connecting said shoe to said eccentric member whereby upon rotation of said eccentric member reciprocable movement may be imparted to said piston, cooperating port means provided in said eccentric member and shoe and opening into said sleeve for supplying a fluid medium through said sleeve into said secondary chamber, and fluid outlet means for said secondary chamber.

5 5. A pump comprising, a casing, a main chamber provided therein, an eccentric member rotatably mounted in said main chamber, a radially directed secondary chamber provided in said casing, a piston reciprocably mounted in said secondary chamber, fluid inlet and outlet means for said secondary chamber, a shoe slidably positioned on said eccentric member, said shoe having a recess formed in the outer surface thereof and said recess having a spherical radius, said piston having a semi-spherical end positioned in one of said recesses, a connecting rod, a first pin for pivotally connecting one end of said rod to said piston, a second pin for pivotally connecting the opposite end of said rod to said shoe, and independent band means for operably connecting said shoe to said eccentric member, whereby upon rotation of said eccentric member reciprocable movement may be imparted to said piston.

20 6. A pump comprising a casing, a main chamber provided therein, an eccentric member rotatably mounted in said main chamber, a radially directed secondary cylindrical chamber provided in said casing, a piston sleeve reciprocably mounted in said secondary chamber, a shoe slidably positioned on said eccentric member, said piston sleeve having an end operably connected to said shoe, a first fluid inlet port formed in said eccentric member and opening radially from said eccentric member, a second port extending through said shoe and said second port being successively opened and closed to said first fluid inlet port, and said second port opening into an end of said piston sleeve, a third fluid outlet port formed in said casing and opening from said cylindrical chamber at the opposite end of said piston, and means operably connecting said shoe to said eccentric member, whereby upon rotation of said eccentric member reciprocable movement may be imparted to said piston sleeve.

25 7. A pump comprising a casing, a main chamber provided therein, a rotatable actuating member mounted in said main chamber, a radially directed secondary cylindrical chamber provided in said casing, a piston sleeve reciprocably mounted in said secondary chamber, a shoe slidably positioned on said actuating member, said piston sleeve having an end operably connected to said shoe, a first fluid inlet port formed in said actuating member and opening radially from said member, a second port extending through said shoe, said shoe having formed in the member contacting surface thereof a recess into which said second port opens, said recess for entrapping a fluid medium in such a manner as to form a fluid bearing for the shoe, said recess being successively opened and closed to said first fluid inlet port by rotation of said member, and said recess opening through said second port into an end of said piston sleeve, a third fluid outlet port formed in said casing and opening from said cylindrical chamber at the opposite end of said piston, and means operably connecting said shoe to said member, whereby upon rotation of said

member, reciprocable movement may be imparted to said piston sleeve.

30 8. A pump comprising a casing, a chamber formed in said casing, a piston sleeve reciprocably mounted in said chamber, a fluid inlet port opening into one end of said piston sleeve, and a fluid outlet port opening from said chamber at the opposite end of said piston sleeve, said piston sleeve being formed of an expansible material, one portion of said piston sleeve being formed relatively thinner than the remaining portion of said sleeve so that expansion of the sleeve at said one portion may be effected upon an increase in the fluid pressure within the piston sleeve so as to decrease fluid leakage between the piston sleeve and the inner surface of the chamber, and means for imparting a reciprocating movement to said piston sleeve in said chamber, including means for opening and closing said fluid inlet port to said piston sleeve in timed relation to said reciprocating movement.

35 9. A pump comprising a casing, a chamber formed in said casing, a piston sleeve reciprocably mounted in said chamber, a fluid inlet port opening into one end of said piston sleeve, and a fluid outlet port opening from said chamber at the opposite end of said piston sleeve, said piston sleeve being formed of an expansible material, and an end portion of said piston sleeve formed sufficiently thin that expansion of the sleeve at said end portion may be effected upon an increase in the fluid pressure within the piston sleeve so as to decrease fluid leakage between the piston sleeve and the inner surface of the chamber, and means for imparting a reciprocating movement to said piston sleeve in said chamber, including means for opening and closing said fluid inlet port to said piston sleeve in timed relation to said reciprocating movement, and valve means for opening and closing said outlet port in response to the forces effected by said piston.

40 10. A pump comprising a casing, a main chamber formed therein, an eccentric means rotatably mounted in said main chamber, a radially directed cylindrical chamber formed in said casing, a piston sleeve reciprocably mounted in said cylindrical chamber, a fluid inlet port opening into one end of said piston sleeve, and a fluid outlet port opening from said cylindrical chamber at the opposite end of said piston sleeve, said piston sleeve being formed of an expansible material, one portion of said piston sleeve being formed relatively thinner than the remaining portion of said sleeve so that expansion of the sleeve at said one portion may be effected upon an increase in the fluid pressure within the piston sleeve so as to decrease fluid leakage between the piston sleeve and the inner surface of the cylindrical chamber, and means operably connecting said piston sleeve to said rotatable eccentric means for imparting a reciprocating movement to said piston sleeve and said eccentric means opening and closing said fluid inlet port in timed relation to said reciprocating movement.

45 11. A pump comprising a casing, a main chamber formed therein, a rotatable eccentric member mounted in said main chamber, a radially directed secondary cylindrical chamber formed in said casing, a piston sleeve reciprocably mounted in said secondary chamber, a shoe slidably positioned on said eccentric member, said piston sleeve having an end bearing upon said shoe and operably connected thereto, a first fluid inlet port formed in said eccentric member, said port open-

ing radially from said eccentric member, a second port extending through said shoe, said shoe having a recess formed in the surface contacting said eccentric member into which recess said second port opens, said recess provided for entrapping a fluid medium in such a manner as to form a fluid bearing between the shoe and the rotatable eccentric member, said recess being successively opened and closed to said first fluid inlet port by said eccentric member upon rotation thereof, said recess opening through said second port into one end of said piston sleeve, the area of the opposite end surfaces of said piston sleeve being acted upon by the pressure of the fluid medium within said cylindrical chamber in such a manner as to cause said piston sleeve to be forced in a direction toward said eccentric member against the biasing force of the fluid medium acting within said recess and against said shoe so as to thereby prevent floating of said shoe from the surface of said eccentric member a third fluid outlet port leading from said cylindrical chamber at said opposite end of said piston, and said eccentric member imparting a reciprocable movement to said piston sleeve upon the rotation thereof.

12. A pump comprising a casing, a main chamber formed therein, an eccentric member rotatably mounted in said chamber, a set of radially directed secondary chambers formed in said casing, a set of radially directed pistons reciprocably mounted in said secondary chambers, fluid inlet and outlet means for said secondary chambers, a set of shoes, slidably positioned on said eccentric member, each of said shoes having a recess formed in the outer surface thereof and said recess having a spherical radius, each of said pistons having a semi-spherical end positioned in one of said recesses, coupling means for pivotally connecting said pistons to said shoes, a pair of rings operably engaging said shoes at the opposite sides thereof in such a manner as to hold said shoes in contacting relation with said eccentric member, snap spring members for coupling said rings together at the opposite sides of said shoes, whereby upon rotation of said eccentric member reciprocable movement may be imparted to said pistons.

13. A pump comprising, in combination, a casting, a main chamber formed therein, an eccentric member rotatably mounted in said main chamber, a set of radially directed secondary cylindrical chambers formed in said casting, a piston sleeve reciprocably mounted in each of said secondary chambers, a separate shoe for each of said pistons, said shoe being slidably positioned on said eccentric member, said shoe having a recess formed in the outer surface thereof, and said recess having a spherical radius, each of said pistons having a semi-spherical end positioned in the recess formed in its corresponding shoe for maintaining alignment between said shoe and piston, a first fluid inlet port formed in said eccentric member and opening radially from said member, second ports extending through each of said shoes, said second ports being successively opened and closed to said fluid inlet port, and each of said second ports opening into one end of said piston sleeves, third fluid outlet ports formed in said casting and opening from each of said secondary chambers at the other end of each of said piston sleeves, each of said piston sleeves being coupled to its corresponding shoe by means including a connecting rod, a first pin for pivotally connecting one end of said rod to the piston sleeve, a second pin for pivotally connecting the opposite end of said rod to said shoe, a pair of annular rings operably engaging said shoes at the opposite sides thereof in such a manner as to hold said shoes in contacting relation with said eccentric member, and means for securing said rings at the opposite sides of said shoes, whereby upon rotation of said eccentric member reciprocable movement may be imparted to said piston sleeves.

sleeve, a second pin for pivotally connecting the opposite end of said rod to said shoe, a pair of annular rings operably engaging said shoes at the opposite sides thereof in such a manner as to hold said shoes in contacting relation with said eccentric member, and means for securing said rings at the opposite sides of said shoes, whereby upon rotation of said member reciprocable movement may be imparted to said piston sleeves.

14. A pump comprising, in combination, a casing, a main chamber formed therein, an eccentric member rotatably mounted in said main chamber, a set of radially directed secondary cylindrical chambers formed in said casing, a piston sleeve reciprocably mounted in each of said secondary chambers, a separate shoe for each of said pistons, said shoe being slidably positioned on said eccentric member, said shoe having a first recess formed in the outer surface thereof, and said recess having a spherical radius, each of said pistons having a semi-spherical end positioned in the first recess formed in its corresponding shoe for maintaining alignment between said shoe and piston, a first fluid inlet port formed in said eccentric member and opening radially from said member, second ports extending through each of said shoes, each of said shoes having a second recess formed in said shoes into which said second port opens, said second recess provided for entrapping a fluid medium in such a manner as to form a fluid bearing between the shoe and the surface of the eccentric member, the second recesses of said shoes being successively opened and closed to said fluid inlet port, and each of said second ports opening into one end of its corresponding piston sleeve, third fluid outlet ports formed in said casing and opening from each of said secondary chambers at the other end of each of said piston sleeves, each of said piston sleeves being coupled to its corresponding shoe by means including a connecting rod, a first pin for pivotally connecting one end of said rod to the piston sleeve, a second pin for pivotally connecting the opposite end of said rod to said shoe, a pair of annular rings operably engaging said shoes at the opposite sides thereof in such a manner as to hold said shoes in contacting relation with said eccentric member, and means for securing said rings at the opposite sides of said shoes, whereby upon rotation of said eccentric member reciprocable movement may be imparted to said piston sleeves.

15. A pump comprising, in combination, a casing, a main chamber formed therein, an eccentric member rotatably mounted in said main chamber, a set of radially directed secondary cylindrical chambers formed in said casing, a piston sleeve reciprocably mounted in each of said secondary chambers, said piston sleeve being formed of an expansible material, whereby expansion of the sleeve may be effected upon an increase in the fluid pressure within the piston sleeve so as to decrease fluid leakage between the piston sleeve and the inner surface of the secondary cylindrical chamber, a separate shoe for each of said pistons, said shoe being slidably positioned on said eccentric member, said shoe having a first recess formed in the outer surface thereof, and said recess having a spherical radius, each of said pistons having a semi-spherical end positioned in the first recess formed in its corresponding shoe for maintaining alignment between said shoe and piston, a first fluid inlet port formed in said eccentric member and opening radially from said member, second ports extending through each of said shoes, each of said shoes having a second recess formed in

said shoes into which said second port opens, said second recess provided for entrapping a fluid medium in such a manner as to form a fluid bearing between the shoe and the surface of the rotatable eccentric member, the second recesses of said shoes being successively opened and closed to said fluid inlet port, and each of said second ports opening into one end of its corresponding piston sleeve, third fluid outlet ports formed in said casing and opening from each of said secondary chambers at the other end of each of said piston sleeves, each of said piston sleeves being coupled to its corresponding shoe by means including a connecting rod, a first pin for pivotally connecting one end of said rod to the piston sleeve, a second pin for pivotally connecting the opposite end of said rod to said shoe, a pair of annular rings operably engaging said shoes at the opposite sides thereof in such a manner as to hold said shoes in contacting relation with said eccentric member and means for securing said rings at the opposite sides of said shoes, whereby upon rotation of said eccentric member reciprocable movement may be imparted to said piston sleeves.

16. A pump comprising, in combination, a casing, a main chamber formed therein, an eccentric member rotatably mounted in said main chamber, a set of radially directed secondary cylindrical chambers formed in said casing, a piston sleeve reciprocably mounted in each of said secondary chambers, said piston sleeve being formed of an expansible material, whereby expansion of the sleeve may be effected upon an increase in the fluid pressure within the piston sleeve so as to decrease fluid leakage between the piston sleeve and the inner surface of the secondary cylindrical chamber, a separate shoe for each of said pistons, said shoe being slidably positioned on said eccentric member, said shoe having a first recess formed in the outer surface thereof, and said recess having a spherical radius, each of said pistons having a semi-spherical end positioned in the first recess formed in its corresponding shoe for maintaining alignment between said shoe and piston, a first fluid inlet port formed in said eccentric member and opening radially from said member, second ports extending through each of said shoes, each of said shoes having a second recess formed into which said second port opens, said second recess provided for entrapping a fluid medium in such a manner as to form a fluid bearing between the shoe and the surface of the rotatable eccentric member, the second recesses of said shoes being successively opened and closed to said fluid inlet port, and each of said second ports opening into one end of its corresponding piston sleeve, third fluid outlet ports formed in said casing and opening from each of said secondary chambers at the other end of each of said piston sleeves, each of said piston sleeves being coupled to its corresponding shoe by means including a connecting rod, a first pin for pivotally connecting one end of said rod to the piston sleeve, a second pin inserted through the opposite sides of said shoe for pivotally connecting the opposite end of said rod to said shoe; a pair of annular rings positioned at the opposite ends of said pins for securing the same in place and engaging said shoes at the opposite sides thereof in such a manner as to hold said shoes in contacting relation with said eccentric member and snap spring members for coupling said rings together at the opposite sides of said shoes, whereby upon rotation of said eccentric member reciprocable movement may be imparted to said piston sleeves.

17. A pump comprising a chamber, a piston sleeve slidably mounted in said chamber, an eccentric member for actuating said piston sleeve in said chamber, a shoe contacting said member and operably connected to said piston sleeve, a recess formed in the contacting surface of said shoe for entrapping a fluid medium during the pressure stroke of said piston sleeve so as to form a fluid bearing between the shoe and the member, said piston sleeve at one end engaging said shoe for reciprocable movement by said member, the surface areas of said shoe and piston sleeve being so arranged that the fluid medium acting upon said shoe in a direction to float said shoe from off said member will be overbalanced by the forces of said fluid medium acting upon said piston sleeve in a direction to force said shoe into contacting relation with said member.

18. A pump comprising a casing, a main chamber formed therein, a pair of axially spaced rotatable eccentric members mounted in said chamber, two sets of axially spaced radially directed secondary cylindrical chambers formed in said casing, two sets of axially spaced radially directed piston sleeves reciprocably mounted in said secondary cylindrical chambers, each of said piston sleeves being formed of an expansible material, whereby limited expansion of the sleeve may be effected upon an increase in the fluid pressure within the piston sleeve so as to decrease fluid leakage between the piston sleeve and inner surface of the secondary cylindrical chamber, a separate shoe for each of said pistons, said shoe being slidably positioned on said eccentric member, said shoe having a first recess formed in the outer surface thereof, and said recess having a spherical radius, each of said pistons having a semi-spherical end positioned in the first recess formed in its corresponding shoe for maintaining alignment between said shoe and pistons, a first fluid inlet port formed in said member and opening radially from said member, second ports extending through each of said shoes, each of said shoes having formed in the member contacting surface of said shoes a second recess into which said second port opens, said second recess provided for entrapping a fluid medium in such a manner as to form a fluid bearing between the shoe and the surface of the eccentric member, the second recesses of said shoes being successively opened and closed to said fluid inlet port, and each of said second ports opening into one end of its corresponding piston sleeve, third fluid outlet ports formed in said casing and opening from each of said secondary chambers at the other end of each of said piston sleeves, a check valve in each of said outlet ports for opening and closing said outlet ports in response to the pressure and suction forces effected by said piston sleeves, each of said piston sleeves being coupled to its corresponding shoe by means including a connecting rod, a first pin for pivotally connecting one end of said rod to the piston sleeve, a second pin inserted through the opposite sides of said shoe for pivotally connecting the opposite end of said rod to said shoe; a pair of annular rings positioned at the opposite ends of said pin for securing the same in place and engaging said shoe at the opposite sides thereof in such a manner as to hold said shoes in contacting relation with said eccentric member, and snap spring members for coupling said rings together at the opposite sides of said shoes, whereby upon rotation of said eccentric members reciprocable movement may be imparted to said piston sleeves.

19. A pump comprising, in combination, a housing, a main chamber provided within said housing, an abaxial, actuating member rotatably mounted in said chamber, a set of radially directed secondary chambers provided in said housing, a set of radially directed piston sleeves slidably mounted in said secondary chambers, a driving shaft for said abaxial member, a fluid inlet passage extending axially in said shaft, an arcual port formed in said abaxial member extending radially from said passage, said piston sleeves op-
erably connected along the peripheral surface of said abaxial member for reciprocable movement in said secondary chambers upon rotation of said shaft, and said arcual port periodically opening into said main chamber and into said secondary chambers through said piston sleeves upon rotation of said shaft, whereby a fluid medium may be drawn through said inlet passage and directed under centrifugal force into said secondary chambers.

JAMES E. BEVINS.
